(54) COOKING STOVE

(76) Inventor: **Gould Thorp**

Gould Sharp, New York,
Letters Patent.

The schedule referred to in these Letters Patent,
and making part of the same containing a description in the words
of the said Gould Sharp himself of his improvement in the baking stove.

To all to whom it may concern:

Be it known that I Gould Sharp of the City of New York have
invented certain improvements in the baking stove for which as
Letters Patent of the United States were granted to Philo L. G.
Holly on the first day of March 1833; and I do hereby declare that
the following is a full and exact description of my said improve-
ment.

I do not think it necessary to describe the said Holly stove,
as it is well known and is now public property, and the specification
of it is in the Patent Office. The improvement which I have made
consists principally in the arrangement of the part for carrying off
the smoke a double sliding damper is opened close certain fire, and
the continuing of the fire place so as to economize fuel. The smoke
pipe hangs at the back part of the stove immediately over the fire below
the oven, and smoke and steam pass the whole width of the oven, part of
the flame, which generally goes to terminate in the smoke pipe, in a
way similar to that adopted by Holly, or instead of this, a tube or
tubes, which are turned back so as to enter a chimney or otherwise, from
the great length of the throat or flue of this fire in front it comes
effectually the smoke of the stove from the boiler. It is made to imme-
diately over the fire. Leaving the fire for heated air all around the oven,
as made by Holly. The upper flue being below the chimney above
mentioned, and smoke dampers or shutters to close the vertical flue
at front and back, so as that the oven may be heated by opening

and/or bars from one to the other, so that they may both be connected upon by one common bed, or bar, and extending through the back or front plate of the cover; by moving this when one of these slides is closed the other is entirely open, or the dampers may be moved so far only as to leave them both partially open, thus affording an opportunity to regulate and direct the draft in any way which may be desired. In order to protect the fire place, and yet allow the fire to not directly and fully upon the bottoms of the boilers immediately over the fire, by bringing the lower plate of the cover forward into the fire place, say three or four inches more or less, it then hangs down vertically and then again turns horizontally and meets the back plate of the fire place; by increasing or diminishing the step formed by the projection and bending of the lower cover plate, as described, the fire place may be protected in any desired proportion, allowing sufficient depth for the bottoms of the boilers etc. The boiler plate above the fire may have its two openings the cover is to one by the division plate between them being made moveable as is done in some other stoves. I also make an opening for a boiler in the cover, by connecting flue plates which constitute the steam flue by means of a iron. What I claim as my improvement to upon Hally's stove, is the constructing of the steam flue in manner above described; the double sliding dampers operating in the manner and for the purpose set forth; and the means of protecting the fire place by bringing the back plate thereof forward.

Witnessed.
